METHODS FOR INVESTIGATING WELLS

Maurice P. Lebourg, Houston, Tex., assignor, by mesne assignments, to Schlumberger Well Surveying Corporation, Houston, Tex., a corporation of Texas

Application May 16, 1955, Serial No. 508,387

7 Claims. (Cl. 324—34)

This invention relates to methods for investigating wells and, more particularly, pertains to new and improved methods for obtaining indications to facilitate the positioning of elements along a tubular member traversing a well drilled into the earth.

Various types of completion systems are presently employed in producing hydrocarbons from wells. Certain of these systems require the use of at least one valve positioned at a considerable depth along the tubing set in the well. For instance, gas-lift equipment includes a plurality of valves distributed along the tubing for selectively effecting fluid communication between the tubing and the annulus defined by the tubing and the casing. These valves, for example, may be set in pockets offset within the tubing, and in certain cases they may be retrieved and reset through the use of a special tool run on a wire line.

Although retrievable valves have proven to be a desirable feature in gas-lift systems, it is often difficult for the operator to be certain that a valve has been properly set in its pocket. Moreover, experience has shown that in some cases where the valve has not been properly set, it may fall to the bottom of the well. In addition, through an operating error, a valve calibrated to a pre-calculated pressure may be set in the wrong pocket.

Another variety of well completion equipment includes an internal sleeve valve that may be shifted by a wire line tool to establish, or shut off, communication between the tubing and the casing. Here, it is not always possible to ascertain whether the sleeve has been properly shifted into one of its two operating positions.

It is, therefore, an object of the present invention to provide new and improved methods for locating anomalies, such as valves, and/or valve pockets, or elements of valves, distributed along the tubing which traverses a well.

Another object of the present invention is to provide a new and improved method for ascertaining whether a valve has been properly set in a pocket in the tubing of a gas-lift oil production system.

A further object of the present invention is to provide a new and improved method for determining whether the correct valve has been set in a particular pocket of a gas-lift system.

A still further object of the present invention is to provide a new and improved method for determining whether a wire-line operated valve has been properly actuated.

These and other objects of the present invention are attained by deriving an electrical signal in response to a change in the ferromagnetic characteristics along the tubing traversing the well and obtaining indications of the electrical signal as a function of depth in the well.

The novel features of the present invention are set forth with particularity in the appended claims. The present invention, both as to its organization and manner of operation, together with further objects and advantages thereof, may best be understood by reference

2

to the following description taken in connection with the accompanying drawings in which:

Fig. 1 is a view in longitudinal cross section of a portion of gas-lift system shown in association with apparatus for carrying out the method embodying the present invention.

Figs. 2, 3A, 3B and 4 illustrate typical records which may be obtained through the use of the apparatus schematically illustrated in Fig. 1.

Figs. 5A and 5B represent a control-sleeve-operated valve, partly in longitudinal cross section, shown in closed and open conditions, respectively; and

Figs. 6A and 6B illustrate typical records which may be obtained in accordance with the present invention for the respective conditions of the valve shown in Figs. 5A and 5B.

In Fig. 1 of the drawing there is shown a tubing string including sections 15 and 16 connected together by a threaded joint 17 and extending downwardly through an oil well casing 18. Of course, while a great many tubing sections are usually employed so that the tubing string extends to a depth of several thousand feet, for the sake of simplicity in the representation only a limited number of sections have been illustrated, and the customary well-head assembly has been omitted.

Threaded to the lower end of tubing section 16 is a mandrel 19 having an offset section 20. A valve-receiving pocket 21 is positioned at the lower end of offset 20 and receives a gas-lift valve 22, and additional tubing sections (not shown) extend from the lower end of mandrel 19. Although a single pocket and its corresponding valve have been illustrated, it will be understood that usually as many as six or eight valves are positioned in pockets distributed along the tubing string, each one calibrated to a precalculated pressure. The tubing sections 15 and 16, the tubing joint 17 and the mandrel 19 are usually constructed of steel, while pocket 21 is constructed of a corrosion-resistant material, such as an alloy of nickel and copper commonly referred to as "Monel." Since "Monel" is a relatively non-magnetic material compared to steel, the location of pocket 21 may be determined by running a device responsive to magnetic properties through the tubing string and the mandrels. For example, a housing 23 enclosing a casing collar locator, for example, of the type described in Patent 2,558,427 is supported by a cable 24 so that it may be lowered into the well. Of course, any other known type of reluctance-responsive device may be suitably employed.

The apparatus within housing 23 is connected via insulated conductors (not shown) of cable 24 to a recorder 25 located at the surface of the earth. The recorder may, for example, comprise a recording voltmeter in which the recording medium is displaced in proportion to movement of the housing through the well. Thus continuous record of magnetic anomalies is obtained as a function of depth in the well.

In operation, and in accordance with the method embodying the present invention, the casing collar locator 23 is lowered into the well and as it passes between tubing sections 15 and 16 the ferromagnetic anomalies produced by joint 17 are recorded. For example, the resulting record may have the appearance illustrated in Fig. 2 which is a plot of voltage as a function of depth. This record includes a response 30 characterizing the casing joint 17.

As the casing collar locator 23 encounters the "Monel" valve-receiving pocket 21, fluctuations 32 and 33 are derived. It will be observed that responses 32 and 33 have a relative spacing representative of the longitudinal dimension of pocket 21 and that they are easily distinguishable from response 30. Consequently, these anomalies may be

independently identified and located as to their depth in the well. It may thus be seen that in accordance with the present invention an electrical signal is derived in response to a change in the ferromagnetic characteristics along the tubing traversing a well and indications are obtained of the electrical signal as a function of depth in the well. Accordingly, the valve-receiving pockets may be accurately located from the surface of the earth.

In order to determine whether a valve is properly set in its pocket, the valve may be provided with a small permanent magnet at its upper end 26. Thus, as shown in Fig. 3A the record produced in response to the signal from casing collar locator 23 contains an additional undulation 34 in addition to the undulations 32' and 33' which represent the valve-receiving pocket 21. The spacing between undulations 34 and 32' provides an indication as to whether the valve is properly seated. For example, as shown in Fig. 3B, an improperly seated valve produces an undulation 34' spaced at a greater distance from undulation 32'' than the spacing between the corresponding undulations 34 and 32' of Fig. 3A. Accordingly, it is obvious to the operator that the valve is not properly seated and the valve is reseated.

If desired, the same method may be applied for properly seating blind plugs which are set in place of valves.

By using a number of small magnets spaced along the longitudinal axis of each valve, the valves may be coded in accordance with their various pressure ratings. For example, as shown in Fig. 4, the record derived in the recorder 25 may exhibit two undulations 35 and 36 for a particular valve (not shown) provided with two magnets. These are followed by undulations 37 and 38 representing the corresponding valve pocket. Further along the tubing, casing collar locator 23 may encounter another valve (not shown) having three magnets and thereby producing undulations 39, 40 and 41 followed by the undulations 42 and 43 representing the corresponding pocket. Since the pockets may be identified in their successive order along the tubing, the coding for each of the valves serves to identify it. Accordingly, an operator may ascertain whether a particular valve has been set in the correct pocket.

It is thus apparent that the method of investigating wells embodying the present invention may be employed to ascertain whether a valve has been properly set in its pocket as well as to determine whether the correct valve has been set in a particular pocket. Therefore, the uncertainty which formerly existed in placing gas-lift valves may be obviated through the use of the method in accordance with the present invention.

Obviously, the method above-described may be used to check the position of the control sleeve in an arrangement wherein a valve is set externally to the tubing. This may be accomplished in the use of a valve of the type illustrated by Fig. 5A where the valve is shown to comprise a tubular body 50 having upper and lower threaded ends 51 and 52 for association with well tubing. Supported within a cylindrical bore 53 of body 50 is a slidable sleeve 54 having a plurality of openings 55. In the position shown, these openings are effectively closed by the wall of bore 53, however, when sleeve 54 is shifted to the position shown in Fig. 5B, at least one of the openings 55 is aligned with a port 56 communicating with a channel 57 that extends to the outer surface of a side extension 58 of member 50.

To determine the position of the member 54 relative to member 50, a pair of small permanent magnets 59 and 60 are set into respective openings in each of these members. In the operating condition shown in Fig. 5A, the magnets 59 and 60 are vertically spaced from one another and when the instrument 23 is run through the tubing to which member 50 is connected, recorder 25 produces a trace having two deflections 61 and 62 as shown in Fig. 6A. The spacing between these deflections represents the spacing between the magnets and thus it may be deter-

mined whether sleeve 54 is properly set at its upper position, fully closing the valve.

When the valve sleeve is in its fully open position, magnets 59 and 60 are adjacent one another, and the recorded trace exhibits only one deflection 63 as shown in Fig. 6B. Accordingly, any deviation from the fully open position will be evidenced by the appearance of a second deflection.

It is, therefore, evident that the method embodying the present invention may be employed to ascertain the operative condition of a sleeve-operated valve. This procedure, of course, may be applied to any sleeve-operated valve, for example, of the type used to circulate between the tubing and the casing.

While particular embodiments of the present invention have been described, it is apparent that changes and modifications may be made without departing from the invention in its broader aspects, and therefore the aim in the appended claims is to cover all such changes and modifications as fall within the true spirit and scope of this invention.

I claim:

1. A method for establishing a selected condition of a valve positioned along a tubular member traversing a well which comprises the steps of magnetically coding a movable portion of the valve relative to a fixed portion of the valve, displacing said movable portion toward a position for said selected condition, deriving an electrical signal representing variations in the ferromagnetic characteristics along the tubular member, said electrical signal exhibiting a response to said magnetic coding thereby denoting the relative positions of said fixed and said movable portions of said valve; and obtaining indications of said electrical signal.

2. A method for establishing a selected condition of a valve having a control sleeve movable relative to a fixed member, said valve being positioned along a tubular member traversing a well, which comprises the steps of magnetically coding each of said control sleeve and said fixed member to exhibit magnetic anomalies spaced from one another relative to the longitudinal axis of the tubular member when the valve is in one operating condition and substantially aligned with one another when the valve is in another operating condition, displacing said control sleeve to bring said valve from one operating condition toward said other operating condition, deriving an electrical signal representing variations in the ferromagnetic characteristics along the tubular member, said electrical signal exhibiting a response to said magnetic coding thereby denoting the relative positions of said control sleeve and said fixed member; and obtaining indications of said electrical signal.

3. A method for investigating a well traversed by a tubular member having in association therewith a plurality of movable elements of well completion equipment comprising the steps of coding said elements and portions of said tubular member magnetically and distinguishably from one another, moving at least one of said elements relative to a corresponding coded portion of said tubular member, deriving an electrical signal representing ferromagnetic characteristics along said tubular member, said electrical signal exhibiting responses to said magnetic coding, and obtaining indications of said responses in said electrical signal thereby to denote the relative positions of said one element and said corresponding coded portion of said tubular member.

4. A method for locating valves spaced along a tubular member traversing a well in a gas-lift system comprising the steps of magnetically coding said valves and selected portions of said tubular member to distinguish said valves from one another according to selected characteristics thereof and from corresponding portions of said tubular member, passing a reluctance-responsive device through said tubular member to derive an electrical signal in response to changes in magnetic reluctance.

of material adjacent said device, and producing indications of said electrical signal as a function of depth in the well thereby to denote the relative positions of at least one of said valves and a corresponding portion of said tubular member and to identify said valves.

5. A method for locating a plurality of valves relative to corresponding valve-receiving pockets in a gas-lift system disposed in a well drilled into the earth comprising the steps of magnetically coding said valves to distinguish them from one another in accordance with individual pressure settings, magnetically coding said pockets, distributing said valves in said pockets, passing a reluctance-responsive device through the well to derive an electrical signal in response to a change in ferromagnetic characteristics, and obtaining indications of said electrical signal as a function of depth in the well.

6. A method for positioning a valve relative to a valve-receiving pocket in a gas-lift system associated with a well drilled into the earth which comprises the steps of magnetically coding said valve and said pocket to exhibit distinguishable ferromagnetic characteristics, placing said valve in said pocket, passing a reluctance-responsive device through the well to derive an electrical signal in response to a change in ferromagnetic characteristics of

10

15

20

material adjacent said device, and producing indications of said electrical signal as a function of depth in the well thereby to denote the relative positions of said valve and said pocket.

7. A method for determining the relative positions of relatively movable elements disposed in a well drilled into the earth which comprises the steps of magnetically coding said elements to exhibit distinguishable characteristics, displacing said elements relative to one another, passing a reluctance-responsive device through the well to derive an electrical signal responsive to the magnetic coding of each of said elements, and obtaining indications responsive to said electrical signal thereby to denote the relative positions of said elements.
